United States Patent Office

Des. 206,226

Patented Nov. 15, 1966

206,226

TAPE DECK

Raymond A. Grosso, Royal Oak, Mich., assignor to Minnesota Mining and Manufacturing Company, St. Paul, Minn., a corporation of Delaware

Filed June 29, 1965, Ser. No. 85,943

Term of patent 14 years

(Cl. D26—14)

FIG. 1

FIG. 2

FIG. 3

FIG. 4

FIG. 5

FIG. 1 is a top plan view of a tape deck, showing my new design;

FIG. 2 is a front elevational view;

FIG. 3 is a rear elevational view;

FIG. 4 is a right side elevational view, the opposite side being substantially a mirror image thereof; and

FIG. 5 is a front, top and left side perspective view thereof, to a reduced scale.

The diagonally lined portions of the drawing indicate transparency.

I claim:

The ornamental design for a tape deck, substantially as shown and described.
